UNITED STATES PATENT OFFICE.

JOHN B. DAVIS, OF CLEVELAND, OHIO, ASSIGNOR TO THE W. S. TYLER COMPANY, OF CLEVELAND, OHIO, A CORPORATION OF OHIO.

ELEVATOR-DOOR-OPERATING DEVICE.

1,245,882.

Specification of Letters Patent.

Patented Nov. 6, 1917.

Application filed May 20, 1916. Serial No. 98,825.

To all whom it may concern:

Be it known that I, JOHN B. DAVIS, a citizen of the United States, and a resident of Cleveland, in the county of Cuyahoga and State of Ohio, have invented a new and useful Improvement in Elevator-Door-Operating Devices; and I do hereby declare the following to be a full, clear, and exact description thereof.

10 My invention pertains to elevator-door-operating devices, and relates especially to operating devices for elevator-doors of the type in which two doors are employed to close the opening, the doors, when in their 15 open position, nesting one behind the other. It is the principal object of my invention to provide a simple, strong and efficient operating device for causing one of said doors to move at twice the speed of the other door, 20 whereby, by actuating one or the other of the doors, both of them can be moved from their nested open position into a closed position in which one door forms an extension of the other. It is another object of my 25 invention to provide a door-operating mechanism of this character which will take up but little space, and which can be located above the doors. It is another object of my invention to provide a mechanism of 30 this character which will permit the doors to slide easily, and enable them to be operated with a minimum of effort. Other objects of my invention will appear from the following specification taken in connection 35 with the annexed claims.

By way of example, I have shown in the accompanying drawings, and described in the following specification, one form of door-operating device constructed in accordance with my invention. It is to be understood, however, that the invention may be embodied in other forms, and that changes may be made in the form described and shown, without exceeding the scope thereof 45 as defined in the appended claims.

In the drawings:

Figure 1 is a plan of an elevator door opening provided with sliding doors and a door operating mechanism constructed in accordance with my invention;

Fig. 2 is an elevation of the same, viewed from the rear, showing the doors in their open position;

Fig. 3 is a view similar to Fig. 2, but showing the doors in their closed position;

Fig. 4 is an enlarged section, the section being taken on the line 4-4 of Fig. 3, looking in the direction of the arrows; and

Fig. 5 is an enlarged detail section taken on the line 5-5 of Fig. 3, looking in the direction of the arrows.

Like reference characters refer to like parts throughout the following specification and the several figures of the accompanying drawings.

Extending lengthwise of the door-way, at the front of the same and above the doors, are a pair of parallel tracks 10, 10^a having V-shaped grooves 11 therein. Running in the grooves 11, are bearing members, each 7.0 of which includes a spacing bar 12 having a plurality of holes formed therein for the reception of balls 13, the latter being held in place by means of lugs 14 on the spacing bar. The balls 13 also engage in V-shaped 7.5 grooves 15 of track members 16 and 16^a respectively.

The track members 16 and 16^a are connected, by means of elongated brackets 17, with doors 18 and 18^a, of which the door 80 18 will hereinafter be referred to as the "slow door," and the door 18^a will be hereinafter referred to as the "fast door." In their open position, the doors 18 and 18^a are disposed behind each other, as shown in 85 Fig. 3. In the closed position of the doors, the fast door 18^a forms an extension of the slow door 18, the two doors closing the opening, as shown in Fig. 2. It will be seen that, when the doors are moved from the 90 position shown in Fig. 2 to the position shown in Fig. 3, the door 18^a is moved twice the distance, and at twice the speed, of the door 18.

The tracks and track members are covered 95 by a casing which includes a front plate 19, a rear plate 20, and a top plate 21, such casing being constructed so as to provide a space at the rear sufficient to inclose the operating mechanism now to be described.

The operating mechanism comprises a pulley frame including side bars 22 which carry, at the ends thereof, spindles for the pulleys 23. One of the side bars 22 of the pulley frame is connected, by means of brackets 24, 105 with the track member 16^a of the slow door. Around the pulleys 23 passes an endless band or chain 25, which is connected to the top plate 21 of the casing, by means of a bolt 26, or the like. The chain is likewise 110

connected, close to the pulley adjacent the closed side of the door-way, with the bracket 17 of the fast door 18^a, the connection being made by means of a bracket 27 carrying suitable means for adjusting the tension of the chain or band.

In the movement of the pulley frame from right to left, any point on the lower part of the band or chain 25 moves at twice the speed at which the pulley frame moves. Consequently, if the slow door 18, which is connected to the pulley frame, is manually moved from its position in Fig. 2 to its position in Fig. 3, the fast door 18^a, being connected to the chain or band, will be moved thereby from the position shown in Fig. 2 to the position shown in Fig. 3—*i. e.*, twice the distance of the slow door. The door may equally well be operated, of course, by actuating the fast door, which will result in the slow door being moved half the distance.

The device described above provides a very simple and efficient means for operating an elevator door of the type in which one door must move a farther distance than the other in opening and closing. The doors move very easily, and can be operated with very little effort; moreover, there are no parts which are at all liable to get out of order. The construction is such that all of the devices may be mounted in a comparatively small space immediately above the door.

Having thus fully described my invention, what I claim as new and desire to secure by Letters Patent, is:—

1. In a door operating device, in combination, a stationary front track and a stationary rear track, said tracks being disposed parallel with each other and spaced apart, ball carriages coöperating with said tracks, a movable front track coöperating with the ball carriage of said stationary front track, a movable rear track coöperating with the ball carriage of said stationary rear track,

a door hanger connected with said movable front track and extending downward between said stationary tracks, a second door hanger connected with said movable rear track and extending downward at the rear of said stationary rear track, a frame extending longitudinally of said tracks, a connecting bar between said movable front track and said frame, said bar extending over said movable rear track, pulleys carried at the ends of said frame, an endless band passing around said pulleys, means for connecting said band, below said pulleys, to the hanger of said movable rear track, and means for securing a portion of said band against movement.

2. In a door operating device, in combination, a stationary front track and a stationary rear track, said tracks being disposed parallel with each other and spaced apart, and having longitudinal V-shaped slots therein, a movable front track and a movable rear track each having V-shaped slots therein, said movable tracks being disposed above said stationary tracks, ball carriages disposed between said tracks and coöperating therewith, a door hanger connected with said movable front track, a pulley frame including longitudinal side members, a bracket secured to said movable front track and extending over said movable rear track, said frame being parallel to and about the same level with said tracks, a casing inclosing said tracks and said frame, pulleys carried at the ends of said frame, an endless band passing around said pulleys, said band being secured above said pulleys to the top of said casing and below said pulleys to the hanger on said movable rear track.

In testimony whereof, I the said JOHN B. DAVIS have hereunto set my hand.

JOHN B. DAVIS.
